UNITED STATES PATENT OFFICE.

JOSEPH ALEXANDREW McGOWEN, OF GALLION, LOUISIANA.

GIN-SAW-FILING MACHINE.

SPECIFICATION forming part of Letters Patent No. 653,358, dated July 10, 1900.

Application filed August 8, 1899. Serial No. 726,610. (No model.)

To all whom it may concern.

Be it known that I, JOSEPH ALEXANDREW McGOWEN, a citizen of the United States, residing at Gallion, in the parish of Morehouse 5 and State of Louisiana, have invented certain new and useful Improvements in Gin-Saw-Filing Machines, of which the following is a specification.

My invention relates to that class of filing- 10 machines known as "gin-saw-filing" machines; and the object of the invention is to provide a machine which will be simple in construction and adapted to thoroughly and expeditiously file the teeth of the saw and 15 otherwise serve the purposes for which it is intended.

With this end in view the invention consists in the novel construction and combination of parts, as will be hereinafter more in 20 detail described, illustrated in the drawings, and particularly pointed out in the claim.

In the accompanying drawings, to which reference is had and which fully illustrate my invention, Figure 1 is a top or plan view of 25 the device, showing the cap or cover supporting the ratchet mechanism removed. Fig. 2 is a side elevation of the same complete, and Figs. 3, 4, 5, 6, and 7 are detail views thereof. Fig. 8 is a plan of the machine detached from 30 its frame.

A designates a rectangular bed-piece upon which is carried the operating mechanism of my device, the said bed-piece being in turn supported upon trestle-benches *u* and trans- 35 versely-arranged seat-piece *T* at one end and is held rigidly in place by means of guide-clamps *X* and an adjustable set-screw *x*, and at its opposite end it has secured to it a spring bifurcated bar *W*, which supports this end 40 and straddles a saw upon the arbor and rests upon the arbor, so as to put the files in line with the teeth on said saw or cylinder, one end each of the trestle-benches being mortised to each end of the seat-piece, the oppo- 45 site ends of these trestle-benches supporting a shaft *T'*, which is journaled in bearings *tt*, carrying a saw *V*, provided with tangentially-arranged teeth *v*. Upon this bed-piece *A* are centrally mounted and rigidly secured at their 50 lower ends standards *B B' B² B³*, the heights of the standards *B B'* being the same and ar-

ranged upon opposite sides of the bed-piece *A* and parallel to each other, while the standards *B² B³* are of different heights, *B²* being somewhat higher than *B³*, the latter being secured at its lower end to one side and near the rear end of the bed-piece. Secured to the tops of the standards *B B² B³* is an inclined bar *H*, slotted, as at *h'*, at one end, and is provided with a pin *i*, the slot in the bar *H* traversing the pin *i* and by which the length of the bar *H* is regulated, and at its opposite end is secured a plate *M*, the under side of which is in the form of an inverted pyramid and sharpened upon its edges, the said plate passing between the saw-teeth and placing the saw in position for the next tooth to come in contact with the files. The bar *H* is connected to an inclined support *h* through the medium of the link *h²*, perforated link *I*, and lever *S*, the lever *S* being pivotally secured to the forward end of a block secured to the rear end of the part *h* and passed through and working in a slot in the part and having a slot *s* in its upper end at one side, within which plays the outer end of the link *I*, and interposed between the link *I* and inclined part *h* is a spring *I'*, secured at one end to the part *h*, its free end bearing upon the under side of the link *I*, having a slot *i'* therein, which is in alignment with the slot *i²* in the link *I* and through which is passed a set-screw *K*. The set-screw *K* is also passed into the part *h*, whereby the stroke of the bar *H* is regulated, the bar *H*, link *h²*, link *I*, spring *I'*, set-screw *K*, and lever *S* constituting the feeding mechanism, said mechanism being raised or lowered, as desired, by means of the set-screw *K*. The lower end of the lever *S* is bifurcated and engages a pin in a reciprocating bar *E*, to which the file-carriers to be hereinafter described are secured. The inclined bar *H* is projected beyond the bed-piece, and the plate upon the free end thereof engages the teeth of the cylinder. 95

E designates a reciprocating operating-bar which is passed through and works in guides *b b*, secured upon the inner sides of the standards *B B²*, clearly shown in Fig. 1 of the drawings, said bar being pivotally connected to the lower end of the lever *S* by means of a pin *s'* in a slot or bifurcation *s²*, said pin *s'* 100

traversing the bifurcation or slot in the movement imparted to the device.

5 F designate a pair of springs secured to the forward end of the operating-bar E by means of screws f, said springs being placed parallel with each other with their flat sides together and held in position by means of a sliding collar R being passed over the springs, the function of which is to regulate the pressure 10 of the files against the teeth of the saw or cylinder. The opposite ends of these springs are secured in a similar manner to a pair of file-carriers G and which are capable of being set at an upward angle, thus allowing 15 the files to come in contact with the upper side of the tooth only, leaving the side smooth that comes in contact with the lint, and to the inner edges of the carriers are secured a pair of files g, which do not cross each other, but 20 operate one above the other and each on the side next to it, the upper carrier of which has a perforation g' therein, through which is passed a set-screw, (not shown in the drawings,) the end of the screw resting against 25 the lower carrier for spacing and adjusting the carriers relative to each other, the construction of the springs and carriers resembling in form a pair of sheep-shears. (More clearly shown in Fig. 3 of the drawings.)

30 O O designate a double-crank shaft secured in bearings o o to the forward edges of the standards B B', and connected to said double-crank shaft is one end of a link N, the opposite end of said link being connected to 35 the lever S, and upon this double-crank shaft is mounted a fly-wheel D, by means of the revolution of which motion is imparted to the device.

40 From the foregoing description, taken in connection with the annexed drawings, the operation of my device will be obvious; but it may be rehearsed as follows: The operator upon turning the crank of the machine puts in motion the fly-wheel thereon, which in turn 45 imparts motion to the feeding mechanism and duplex files simultaneously, care being taken that the files are straight with the teeth, so that they will file from point to throat, the forward motion of the crank bringing the 50 files in contact with the teeth of the saws, and as the fly-wheel continues its revolutions the files are drawn backward and forces the bar H forward, to the front end of which an adjustable steel plate is secured which passes 55 between the teeth, separating them and revolving the saws sufficiently to bring the next tooth in position for the files as they pass forward on the further turning of the crank, and should the bottom file cut the top of the tooth 60 faster than the file in the top carrier slack the adjustable screw in the wide end of the top carrier until both files cut the same, and if the top file cuts faster tighten the screw, and if the files cut the point of the tooth too 65 fast slacken the left nut in the under side of the bifurcated bar and tighten the oppo-

site nut, and if the files cut the tooth at the point on the under side reverse on the nuts. These nuts govern the pitch of the tooth as the bar works on a pivot. Do not file to a 70 perfect point, as the tooth will bend, and the pressure of the files against the teeth is regulated by a sliding collar, the files operating one above the other and each on the side of the tooth next to it, the file-carriers being 75 spaced by the set-screw passing through the upper one and resting against the lower file-carrier. The function of this sliding collar is also to keep the pressure from crumpling the cutting edges of the files as they wear, 80 the collar being moved out on the springs to keep the files cutting the same. The machine is so adjusted that a forward motion of the crank files the tooth and that as the crank turns over the files are drawn back and the 85 ratchet mechanism revolves the saw or cylinder with perfect uniformity, both working on the same crank and nicely balanced by the fly-wheel. The filing of the under side of the tooth is avoided by adjusting the file-carriers by means of screws at the forward ends of the springs, giving the carriers an upward angle. The cylinder is turned in such a manner as to get a downward motion of the files to file the top of the tooth and not the bottom, which allows the cotton to slip readily 90 into the throat of the teeth, forcing the gin to take the lint from the seed and at the same time will not cut or nap the lint, thus saving it in a perfect state and also saving the files. 95 When the ratchet is lowered, if the cylinder rotates from the force of the files tighten the bearings or cylinder-journal until the files have no effect on the cylinder, and if the plate on the bar H moves back over more 100 than one tooth at a time tighten down the thumb-screw, which shortens the stroke, and if it does not move over one tooth slacken this screw. This screw governs the stroke of the bar H, and if the plate does not fit in the 105 tooth take up or let out by tightening or slackening set-screw, which fastens bar H and its rear link as it may need to make the plate fit the teeth. Do not tighten the bearings so tight 110 as to slip the teeth off the saws, and if the files do not cut the top of the teeth and leave the bottom smooth set the file-carriers a little more up at the small ends, as they should 115 have a downward movement as they perform their stroke on the saws.

120 Having thus described my invention, what I claim as new, and desire to secure by Letters Patent, is—

The combination with the trestles u, and T, bed-piece A, secured to the transverse piece 125 T, clamp X, adjustable thumb-screw x, bifurcated bar W, ratchet mechanism consisting of the adjustable slotted ratchet-bar H, provided with the inverted pyramidal plate M, pin i, link h², slotted link I, spring I', lever S, set-screw K, cap or cover h, and its rear block secured thereto; of the reciprocating 130

bar E, standards B, B', B², B³, springs F, F, provided with the collar R, secured to the bar E, adjustable file-carriers G, G, secured to the springs F, F, one of which is provided 5 with the perforation g', files g, secured to the carriers, double-crank shaft journaled in the standards B, B' link N, connecting crank-

shaft to the ratchet-lever S, and fly-wheel mounted upon the crank-shaft, substantially as and for the purpose set forth.

JOSEPH ALEXANDREW McGOWEN.
